PREASSEMBLED MODULAR HOUSING
STRUCTUREEdward D. Kelbish, 280 Vanderbilt Ave.,
New York, N.Y. 11205

Filed July 14, 1972, Ser. No. 272,029

Term of patent 14 years

Int. Cl. D25—03

U.S. CL. D13—1 A

FIG. 1.

FIG. 2.

FIG. 3.

FIG. 4.

FIG. 5.

FIG. 6.

FIG. 1 is a roof plan view indicating the plan relationship of the six (6) housing modules and the two (2) deck modules of my new design;

FIG. 2 is a side elevational view of the modular housing structure in FIG. 1;

FIG. 3 is a side elevational view of the modular housing structure in FIG. 1;

FIG. 4 is a rear elevational view of the modular housing structure in FIG. 1;

FIG. 5 is a front elevational view of the modular housing structure in FIG. 1;

FIG. 6 is a perspective view indicating the design relationship of the six (6) housing modules and the one (1) visible deck module of the modular housing structure in FIG. 1.

I claim:

The ornamental design for a preassembled modular housing structure, as shown.
